(57) **CLAIM**

An ornamental design for a vehicle upper rear bumper cover, shown and described.

DESCRIPTION

FIG. 1 is a top plan view of a vehicle upper rear bumper cover; FIG. 2 is a bottom plan view of the vehicle upper rear bumper cover;

FIG. 3 is front elevational view of the vehicle upper rear bumper cover;

FIG. 4 is a left side elevational view of the vehicle upper rear bumper cover;

FIG. 5 is a right side elevational view of the vehicle upper rear bumper cover; and,

FIG. 6 is a perspective view of the vehicle upper rear bumper cover.

The absence or presence of surfaces on the area enclosed by broken lines is not relied upon for patentability or infringement. The surfaces enclosed by broken lines are illustrated in lighter tones to distinguish them from the claimed surfaces. Any broken lines represent an internal boundary of the design; the line itself and the area within form no part of the claim. Views are orthogonal projections rendered from computer aided design data.

The broken lines shown throughout the drawing are shown for illustrative purpose only and form no part of the claimed design.
